DESIGN FOR A COMBINED CHEST AND DESK

Dorothy B. Allen and Alan A. Allen,
Los Angeles, Calif.

Application March 25, 1947, Serial No. 137,868

Term of patent 3½ years

(Cl. D33—7)

To all whom it may concern:

Be it known that we, Dorothy B. Allen and Alan A. Allen, citizens of the United States, residing at Los Angeles, in the county of Los Angeles and State of California, have invented a new, original, and ornamental Design for Combined Chest and Desk, of which the following is a specification, reference being had to the accompanying drawing, forming part thereof.

The figure is a perspective view of a combined chest and desk, showing our new design.

The back and the side not shown are substantially plain and unornamented.

We claim:

The ornamental design for a combined chest and desk, substantially as shown and described.

DOROTHY B. ALLEN.
ALAN A. ALLEN.
